UNITED STATES PATENT OFFICE.

CHRISTIAN A. HERR, OF OSBORN, OHIO.

DESIGN FOR A TOP FOR GASOLENE-STOVES.

SPECIFICATION forming part of Design No. 29,440, dated October 4, 1898.

Application filed September 8, 1898. Serial No. 690,533. Term of patent 14 years.

To all whom it may concern:

Be it known that I, CHRISTIAN A. HERR, residing at Osborn, in the county of Greene and State of Ohio, have invented and produced a new and original Design for a Gasolene-Stove Top, of which the following is a specification, reference being had to the accompanying drawings, showing a part thereof.

Figure 1 represents a perspective view of my design. Fig. 2 is a top view of the same. Fig. 3 represents a front edge view. Fig. 4 represents a side edge view.

As shown in the drawings, the leading or material feature of my design consists of the unitary article made the subject of illustra-

tion and having a substantially square or rectangular-formed top face 1, as shown in Figs. 1 and 2, and the curved or concaved lower side edges 2, substantially as shown in Figs. 1, 3, and 4, whereby downwardly-extending lugs 3 are provided at each corner of the top.

Having thus described my invention, what I claim as new, and desire to secure by Letters Patent, is—

The design for a top for gasolene stoves or burners, as herein shown and described.

CHRISTIAN A. HERR.
